CLAIM

The ornamental design for a drawer latch, as shown and described.

DESCRIPTION

FIG. 1 is a front perspective view of the drawer latch of the present invention showing my new design;

FIG. 2 is a rear bottom perspective view thereof;

FIG. 3 is a side elevational view thereof, it being understood that the opposite side view is substantially a mirror image, the only difference being the placement of the cylinder;

FIG. 4 is a left end view thereof; and,

FIG. 5 is a right end view thereof.

The broken lines depicting environmental structure in FIGS. 1, 2 and 3 are for illustrative purposes only and form no part of the claimed design.
